[57] CLAIM

The ornamental design for a protective wheel cover, as shown and described.

DESCRIPTION

FIG. 1 is a front perspective view of the protective wheel cover;

FIG. 2 is a back elevation view of the protective wheel cover seen in FIG. 1; and,

FIG. 3 is a left edge elevation view of the protective wheel cover seen in FIG. 1.

The broken lines in FIGS. 1 and 2 represent tear lines.
